FIBER HANDLING MECHANISM

Chesley A. Smith, Seattle, Wash., assignor to
Eddie Bauer, Seattle, Wash.

Application May 8, 1943, Serial No. 486,257

4 Claims. (Cl. 222—70)

In the production of down-filled clothing, quilts, sleeping bags, robes and the like, great difficulty has been experienced in the conveyance of discrete padding from containers into the pockets or pouches of the articles to be padded. These difficulties relate to the maintenance as well as provision of a fiber-bearing air stream having a uniform characteristic at all times. Further difficulties relate to the timing of the flow of a fiber and air stream in accordance with variable requirements of quantities of padding to be placed in various-sized pockets or tubes.

A specific problem arises in the manufacture of sleeping bags that are padded with discrete down or feathers or floss. At the present time, the United States Army is having manufactured great quantities of down-filled sleeping bags for its troops. The approved designs call for a bag roughly having the shape of a frusto-conical envelope. Each wall of the envelope is formed of an inner and an outer membrane. These membranes are either stitched together or have stitched therebetween a dividing wall which subdivides the space between the membranes into tubes or tunnels. Due to the shape of the envelope, these tubes and tunnels will be of different sizes and shapes, and therefore have varying capacities for the padding to be placed therein. It is naturally desirable that the amount of padding in any one tube be uniform in cross-section with that of any of the other tubes. It is practically impossible to insert the padding in this required uniform manner by hand, since the operators usually do not have the judgment necessary to accurately determine when sufficient padding has been inserted into the tubes. Various schemes and arrangements have been made and employed in prefilling various sized measuring containers with fibrous material, then conveying the material from the different containers to the different tubes in accordance with the pattern of the sleeping bag being padded. Other schemes have related to the use of a constantly flowing air stream which carries the padding in whatever manner it may be introduced thereto and leaves it up to the operator to judge when he has permitted the stream to blow enough in a particular tube to place therein the desired quantity of padding.

Neither of the foregoing arrangements, nor any others known to this applicant, has been successful in meeting the high standards and requirements customary in this work.

Having in mind the defects of the prior art, it is a prime object of this invention to provide

fiber handling mechanism suitable for filling articles to be padded, which equipment will largely eliminate guesswork and the human element.

It is another object of this invention to provide means for placing the fiber in air-borne suspension in such a manner that it may be pneumatically conveyed in a uniform stream that can be mechanically controlled.

A further object of the invention is the provision of novel and useful mechanical control means for a pneumatic stream of fiber particles in suspension whereby only predetermined amounts of fiber will be conveyed and discharged.

Still another object of the invention is the provision of a novel and useful mechanical timer mechanism to regulate the flow of a pneumatic stream of air carrying a quantity of fiber.

The foregoing objects and others ancillary thereto I prefer to accomplish as follows:

According to a preferred embodiment of my invention, I convey fiber from a suitable hopper to a manually employed dispensing nozzle by suitable controlled pneumatic means. Specifically, the hopper is provided with mechanical and pneumatic agitation means which operate to place the fiber in a uniform air-borne suspension, all more or less within a well-defined zone in the hopper. This air-suspended fiber within the hopper is drawn into suitable conduit means for conveyance to a dispensing nozzle and is moved in this conduit by conventional blowing equipment. Thus is insured a stream, having uniform characteristics, of air-borne fiber at the nozzle tip. The draft of air-borne fiber through the conduit system is directly controlled by a timer disc having a predetermined pattern, which produces intermittent interruption of the flow of fiber to the conduit system in a controlled sequence of air blasts to provide periods of operation according to the desired requirements that have to be met. The timing mechanism is operable at the instance of the operator under the control of switch mechanism adjacent the manually employed nozzle.

The novel features that I consider characteristic of my invention are set forth with particularity in the appended claims. The invention itself, however, both as to its organization and its method of organization, together with additional objects and advantages thereof, will best be understood from the following description of specific embodiments when read in connection with the accompanying drawings, in which

Figure 1 is a perspective view of my fiber handling mechanism;

Figure 2 is a vertical longitudinal sectional view of the mechanism of Figure 1;

Figure 3 is a horizontal sectional view taken on line 3—3 of Figure 2;

Figure 4 is a vertical transverse sectional view taken on line 4—4 of Figure 2;

Figure 5 is a perspective view of a portion of the fiber agitating equipment employed within the hopper of the foregoing figures;

Figure 6 is a side elevational view of the pattern holder and its operating mechanism, with portions shown in section for convenience of illustration;

Figure 7 is a plan view from the under side of the pattern holder; and

Figures 8 and 9 are diagrammatic showings of the electrical control system governing the flow of an air-borne stream of fiber according to my invention.

Fiber handling equipment, to overcome the defects hereinbefore enumerated, must have at least two totally distinct characteristics; it must be capable of providing an air conveyor stream having uniform quantities of discrete fibers suspended therein; and it must also provide control means for either regularly or variably interrupting the flow of said stream in accordance with predetermined requirements in the placing of the discrete material in padding position in articles being padded. For convenience of description I treat herein the mechanism of this invention first as to the fiber agitation and conveyance means and, secondly, as to the control mechanism and circuits employed in regulating the flow of the fiber conveying air stream. It must be borne in mind, however, that these functions are interdependent and that this separation is only for simplification.

Fiber agitation.

A preferred embodiment of my fiber agitating mechanism is shown in detail in Figures 1 through 5, in which the numeral 10 designates a hopper formed of a plurality of walls and top and bottom panels. In the upper portion of the hopper a door 12 closes a fiber introduction opening 14. The discrete fibers employed in padding articles is usually supplied in large bags which may easily be emptied into the hopper interior.

For the purposes of this description I shall refer hereafter to the fiber as "down," since that is a common and useful material employed in padding garments and sleeping bags. Down is a soft, fluffy undergrowth derived from the feather formation of birds such as duck and goose. It is light in weight as to the individual particles, but in mass tends to intertwine and bunch and pack. My agitation equipment serves to lift and buoy this down in an air-borne suspension in the hopper 10.

At opposed points in the lower portion of the hopper I introduce air by means of the nozzles 16, 16 that receive such air under pressure from suitable blowers (not shown). It is preferable that the nozzles flare toward the discharge slit 20 so that a relatively thin stream of air is introduced across the bottom of the hopper. By opposing these incoming streams of air a buffering action is produced at the point where the two streams collide and converge and deflect upwardly.

Within the hopper mechanical agitation means is also employed and comprises the beaters 22, 22 which are swingably suspended from above by the

depending arms 24 hinged at 26 to the under side of the hopper cover. A reciprocable draw bar 28, joined by cross heads 30, 30 to the arms 22, serves to swing the beaters in a reciprocal path within

5 the chamber in the hopper. Draw bar 28 is reciprocated by the mechanism exterior of the hopper, as shown in Figures 1 and 2, and includes the bell crank 32 that is rocked by the connecting rod 34 through its eccentric connection with the 10 rotary crank disc 36. Power to rotate disc 36 is supplied thereto from motor 38 through a series of speed reducing sheaves 40, 41, 42 and belts 43 and 44. The draw bar is passed into the hopper through opening 46 which is sealed by the flexible 15 boot 48.

Hopper 10 has a supplemental air exhaust conduit 50 shielded by screen 51. A collector bag is shown at 54 to receive the exhaust air from the hopper and to entrap such vagrant down particles as may have passed through the shielding screen 51.

Operation of the agitating equipment.

When a quantity of down is placed in the hopper 25 its natural tendency is to settle to the bottom. Air is forced under the down from the nozzle slits 20 to lift it and assist its movement to the suspension area in the approximate median of the hopper. The two incoming streams each picks up and conveys a portion of the down to the point 30 of collision of the streams and thereafter the down is raised due to the convergence of these streams upward to the suspension area. At the same time as the air is flowing into the hopper, 35 the swinging beaters 22 reciprocate through the fluffy mass of down and continually force the discrete particles into the rising air streams from the input nozzles. The result is that a cloud of down is placed in air-borne suspension in the 40 hopper. This cloud has a uniform content of air and down with the bunches or wads broken up and dispersed throughout.

The operation of the air entering the hopper through the flared nozzle is to buoy and float the 45 down in the upper mid portion of the hopper in the form of a light, fluffy blanket. The two air streams entering the hopper collide and converge or deflect upwardly in the hopper. At the same time the beaters are operating back and forth 50 through the mass and tend to break up the wads and bunches of down in the mass and to distribute it evenly in the air. The result is that a soft, fluffy stratum of relatively uniform density 55 throughout is formed within the hopper through which stratum, in small streams only, the incoming air circulates and bubbles to the upper side. Were it not for the action of the beaters, fairly large air passages would form in the discrete mass and down would separate on either side and 60 not be buoyed. The down would in that case be in a more or less solid mass, not suitable to be withdrawn from the hopper by suction.

Air conveyor mechanism.

65 To move the down from the hopper 10 to the point of use I employ a conduit tube 53 which is connected to the suction side of a motor operated blower 54 that discharges into the tube 55 having the distribution nozzle or feed tube 56. These conduits are preferably flexible as the nozzle is usually manually introduced into the article being padded from various directions. A suction tube 58 is joined with tube 53 by a Siamese coupling 60 which has an air bypass arm 62. At the 70 Y within the coupling 60 is a swinging gate or

valve plate that is actuated by arm 66 to open or close one or the other of the ducts within the Siamese coupling. Arm 66 carries the movable core 68 that is variously inserted into the solenoid 70 against the urging of spring 72 in accordance with the electrical energization of the solenoid.

It is preferable that the fan of blower 54 be constantly operating so that, depending upon the position of valve 64, there will also be available suction either from the bypass opening in arm 62 or from the pick-up opening in tube 58. It is to be noted that the pick-up tube is placed in the hopper at approximately the mid-portion thereof in the down suspension area or closely adjacent thereto.

Operation of the air conveyor

Air-borne down in the hopper is drawn into the conduit at such times as the tube 58 is in communication, due to the position of valve gate 64, with the suction effect of the blower fan 54. In that event, over a given time period, a uniform quantity of air and down will be drawn from the hopper and passed into the conveyor tubes and to the nozzle 56. By predetermining the suction periods measured quantities of down will be passed through the conveyor for use in padding garments.

Control mechanism

The operation of valve 64 to its various positions is governed by an electrical circuit that is in turn activated or deactivated by mechanical means. An upright rotatable spindle 71 mounted in a suitable bearing 72 carries for rotation the sheave 74 driven by belt 76 from the drive sheave 78 which is rotated through speed reducer 80 from the constantly rotating motor 82.

Also supported upon shaft 71 is the pattern disc 84 which carries on its under side clutch spring arms 86 that rest upon the upper face of the sheave 74 to, on occasion, turn the pattern holder disc simultaneously with said sheave. About its periphery the pattern holder is provided with a plurality of notches 88 which are spaced thereon according to a predetermined series of time periods to be delineated in the open positioning of valve 64.

Mounted adjacent disc 84 is a solenoid 90 in which is movable the core 92 that carries a pivoted detent 94 engageable in any of the notches 88 of the pattern disc. On opposed sides detent 94 has a pair of horns 95 and 96, the latter of which is pressed to move the detent toward disc 84 by means of spring arm 98. Horn 95 carries the contact arm 100 to close with opposed contact arm 101, thus forming a switch in the electrical supply lines 102, 103 to solenoid 70. Whenever core 92 is drawn into the solenoid 90 by reason of its energization the pattern disc 84 is freed from the restraint of detent 94 and it will rotate through the action of clutch springs 86 with the constantly rotating sheave 74. At the same time a circuit is completed through the solenoid 70 to swing the arm 66 to open valve 64 in the Siamese coupling of the conduit system. Air-borne down is then drawn into the conveyor system and conducted to the nozzle 56 for so long a period as is measured by the peripheral distance between the notch of disc 84 just disengaged and the next following notch into which the detent 94 will next seat to disrupt the sustaining circuit of solenoid 70, whereupon valve 64 opens to the bypass side and stops the flow of air and down.

Solenoid 90 is manually operated under the

control of the switch 110 in the electrical supply circuit comprising leads 111 and 112. I mount switch 110 on the tube 56 where it is convenient to the operator who, when he desires a flow of down from feed tube 56, presses the switch operating button to initially energize coil 90 to permit free rotation of the pattern disc. When the disc 84 has rotated the distance between adjacent notches the down flow will cease until the switch 110 is next closed. By so arranging the sequence of the notches around the edge of the pattern disc in accordance with the requirements of the garment being padded, as set by the pattern of the pockets and pouches therein, it is possible for an operator to place a desired quantity in each pocket uniformly throughout the garment.

Although I have shown and described certain specific embodiments of my invention, I am fully aware that many modifications thereof are possible. My invention, therefore, is not to be restricted except insofar as is necessitated by the prior art and by the spirit of the appended claims.

Having thus described my invention, I claim:

- 20 1. Mechanism for separately dispensing measured quantities of fluent fibrous material, comprising: a housing to receive fiber; means in the housing operable to place fiber contained therein in air borne suspension; pneumatic means for withdrawing a stream of the suspended fiber from the housing; and means for controlling the operation of the pneumatic means, including: a valve disposable across the stream of withdrawal air, electro-magnetic means for moving said valve, a pattern holder having a predetermined pattern sequentially impressed thereon, and a make and break switch in circuit with said electro-magnetic means and responsive to the pattern sequence set by said pattern-holder.
- 25 2. Mechanism for separately dispensing measured quantities of fluent fibrous material, comprising: a housing to receive fiber; means in the housing operable to place fiber contained therein in air borne suspension; pneumatic means for withdrawing a stream of the suspended fiber from the housing; and means for controlling the operation of the pneumatic means, including: a valve disposable across the stream of withdrawal air, electro-magnetic means for moving said valve, a rotatable cam having a predetermined pattern on the edge thereof, means for rotating said cam, a cam follower movable in accordance with the pattern delineated by said cam, a switch in circuit with said electro-magnetic means and responsive to the movement of the cam follower to close and open the electro-magnetic circuit.
- 30 3. Mechanism for separately dispensing measured quantities of fluent fibrous material, comprising: pneumatic means for moving fiber, a valve for controlling the operation of said pneumatic means, electro-magnetic means for operating said valve, a constantly rotating drive wheel, a pattern disc having edge notches and coaxially mounted adjacent said drive disc, a detent engageable in the notches in the edge of the pattern disc, means operable from a remote point for withdrawing the detent from an engaged notch in the pattern disc, a switch in circuit with said electro-magnetic means responsive to movement of the detent to close and open the electro-magnetic circuit, and clutch means between said drive disc and the pattern disc operable when the detent is withdrawn from the notches to rotate the pattern disc with the drive disc.
- 35 4. Mechanism for separately dispensing meas-

ured quantities of fluent fibrous material, comprising: pneumatic conduit means for moving fiber, a valve for controlling the passage of fiber through said conduit means, electro-magnetic means for operating said valve, a constantly rotating drive wheel, a pattern disc having edge notches coaxially mounted adjacent said drive disc, a detent engageable in the notches of the pattern disc edge, electro-magnetic means for withdrawing the detent from an engaged notch

in the pattern disc, a switch in circuit with said first mentioned electro-magnetic means and responsive to the movement of the detent to close and open the circuit of said first mentioned electro-magnetic means, and clutch means between said drive disc and the pattern disc operable when the detent is withdrawn from the notches to rotate the pattern disc with the drive disc.

10

CHESLEY A. SMITH.
